(57) **CLAIM**

The ornamental design for an facial brush as shown and
described.

DESCRIPTION

FIG. 1 is a front view of a facial brush showing our new
design;

FIG. 2 is a top view thereof;

FIG. 3 is a back view thereof;

FIG. 4 is a front top perspective view thereof;

FIG. 5 is a bottom view thereof;

FIG. 6 is a back top perspective view thereof;

FIG. 7 is a back perspective view thereof;

FIG. 8 is a front bottom perspective view thereof;

FIG. 9 is a front perspective view thereof;

FIG. 10 is a back bottom perspective view thereof; and,

FIG. 11 is a right view thereof.

1 Claim, 11 Drawing Sheets
